(57) **CLAIM**

The ornamental design for a toothbrush handle, as shown and described.

DESCRIPTION

FIG. 1 is a front perspective view of a toothbrush handle for a toothbrush;

FIG. 2 is a back perspective view of a toothbrush handle for a toothbrush;

FIG. 3 is a front perspective view of a toothbrush handle for a toothbrush;

FIG. 4 is a back perspective view of a toothbrush handle for a toothbrush;

FIG. 5 is a side elevational view of a toothbrush handle for a toothbrush;

FIG. 6 is a side elevational view of a toothbrush handle for a toothbrush;

FIG. 7 is a top elevational view of a toothbrush handle for a toothbrush;

FIG. 8 is a bottom elevational view of a toothbrush handle for a toothbrush;

FIG. 9 is a front elevational view of a toothbrush handle for a toothbrush with the toothbrush head and wall-attachment hanger not shown in FIGS. 9-16 for clarity of illustration;

FIG. 10 is a back elevational view of a toothbrush handle for a toothbrush with the toothbrush head and hanger removed;

FIG. 11 is a front view of a toothbrush handle for a toothbrush with the toothbrush head and hanger removed;

FIG. 12 is a back view of a toothbrush handle for a toothbrush with the toothbrush head and hanger removed;

FIG. 13 is a side view of a toothbrush handle for a toothbrush with the toothbrush head and hanger removed;

FIG. 14 is a side view of a toothbrush handle for a toothbrush with the toothbrush head and hanger removed;

FIG. 15 is a top view of a toothbrush handle for a toothbrush with the toothbrush head and hanger removed; and,

FIG. 16 is a bottom view of a toothbrush handle for a toothbrush with the toothbrush head and hanger removed.

The broken lines in the drawing figures illustrating a toothbrush head, a wall-attachment hanger and certain features of the toothbrush handle form no part of the claimed design.

1 Claim, 8 Drawing Sheets
